PLANT GROWTH APPARATUS

R. Louis Ware, 2108 Middle Fork Road,
Northfield, Ill. 60093

Filed Sept. 21, 1970, Ser. No. 25,087

Term of patent 14 years

Int. Cl. D6—05

U.S. Cl. D35—3

FIG. 1

FIG. 2

FIG. 3

FIG. 4

FIG. 1 is a front perspective view of a plant growth apparatus of my new design;

FIG. 2 is a rear perspective view of the design shown in FIG. 1;

FIG. 3 is a front view of the design shown in FIG. 1; and

FIG. 4 is an end view of the design shown in FIG. 1.

The back of the design is identical to the front shown in FIG. 3.

Both ends of the design are identical to the end shown in FIG. 4.

I claim:

The ornamental design for a plant growth apparatus, as shown and described.
